UNITED STATES PATENT OFFICE.

OLGA B. RILEY, OF ROXBORO, NORTH CAROLINA.

DETACHABLE BRACE FOR PLOW HANDLES.

Application filed November 21, 1925. Serial No. 70,496.

This invention relates to new and useful improvements in plows and is more particularly adapted for bracing the handles thereof.

5 One of the important objects of the present invention is to provide a detachable brace for the plow handles whereby the use of the usual stationary rings which extend between the handles is obviated.

10 A further object of the present invention is to provide a device of the above mentioned character which may be easily and conveniently placed in position for supporting the plow handles in a rigid manner, means being provided for preventing the accidental 15 displacement of the device while the same is in use upon the plow.

A still further object is to provide a device of the above mentioned character which 20 is simple in construction, inexpensive, strong and durable and further well adapted for the purposes for which it is designated.

25 Other objects and advantages of this invention will become apparent during the course of the following description.

In the accompanying drawing forming a part of this specification and in which like numerals of reference designate like parts 30 throughout the same,—

Figure 1 is a top plan view of my device showing the same in use.

Figure 2 is an enlarged fragmentary plan view.

35 Figure 3 is a sectional view taken on line 4—4 of Fig. 2.

Figure 4 is a sectional view taken on line 3—3 of Fig. 2, and

40 Figure 5 is a sectional view taken on line 5—5 of Fig. 1.

In the drawing, wherein for the purpose of illustration is shown the preferred embodiment of my invention, the numerals 1 and 2 designate a pair of plow handles 45 which are of the well known construction, the converging ends of which are connected to the plow beam 3 in the usual manner and the outer ends of which are spaced from one another. Heretofore the bracing means employed for holding the handles in properly spaced position consisted of the stationary rungs which extended between the handles adjacent the outer ends thereof. The present invention has for its particular purpose 55 to provide a bracing means which may be detachably associated with the handles and

so supported thereon as to enable the handles to be adjusted to various widths to meet the necessary requirements, as will hereinafter be more fully described.

60 The bracing means in the present invention comprises an elongated plate 4 which is formed preferably of wood although it is to be understood that any other suitable material may be substituted therefor, and tapers 65 gradually towards its outer ends as is clearly illustrated in Fig. 1 of the drawing. Formed in the top face of the elongated plate 4 are the longitudinally extending channels or guides 5 and 6, respectively, in 70 which are adapted to slidably operate the elongated arms 7 and 8, respectively. These channels 5 and 6 have their outer ends terminating at a point adjacent the respective ends of the plate 4.

75 Formed in the bottom face of the plate 4 in alignment with the longitudinally extending channels 5 and 6 are the similar channels 9 and 10 respectively. These channels extend to the outer ends of the plate 4 and the inner ends of the channels formed in the bottom face of the plate 4 and the outer ends of the channels formed in the upper face of the plate terminate in the openings 11 and 12 respectively, the purpose of which will 80 be presently apparent.

85 The elongated arms 7 and 8 which are adapted for slidable movement in the longitudinal channels 5 and 6 respectively terminate at their outer ends in the downwardly extending portions 13 and 14 respectively and the latter are adapted to be received in the openings 11 and 12 formed in the plate 4. The lower portions of the downwardly extending members 13 and 14 have the 90 shorter arms 15 and 16 extending outwardly therefrom and are disposed within the channels 9 and 10 provided in the outer ends of the bottom face of the plate 4, in the manner as clearly illustrated in the drawing.

95 Secured to the outer ends of the shorter arms 15 and 16 respectively and extending transversely thereto are the strips 17 and 18 respectively. These strips 17 and 18 and the adjacent ends of the plate 4 when in position on the plow handles 1 and 2 will form 100 a handle engaging means for holding the brace in position on the plow. For the purpose of controlling the actuation of the arms and the handle engaging portions carried thereby whereby the brace may be detached 105 from or placed in position on the handles

of the plow, I provide the lever 19. This lever is pivotally supported intermediate its ends on the top face of the plate 4 as shown in 20 in the drawing, and is also connected to the inner ends of the arms 7 and 8 respectively by any suitable fastening means, as is illustrated at 21 and 22 in the drawing. This construction enables the arms to be interconnected whereby the simultaneous action of the same is provided. The outer end of the lever 19 extends beyond the outer side of the plate 4 and is provided with a suitable aperture for the purpose of supporting therein the pawl 23. This pawl is preferably constructed so as to provide a double acting pawl for cooperation with the teeth 24 formed in the outer side face of the plate 4 whereby a means is provided for holding the lever 19 and the arms 7 and 8 connected thereto in various adjusted positions so as to cause the strips 17 and 18 to be held in a secured position with respect to the handles 1 and 2 when the device is in use.

23 Also carried by the outer side face of the plate 4 and arranged in spaced relation thereto is the supporting member 25. The latter is adapted to act as a guide means for the outer end of the lever 19 and it is to be understood that the same will form a rest for the outer end of the lever when the latter is actuated. This supporting member 25 further aids in preventing the accidental displacement of the double acting pawl 23 from its operative position with respect to the teeth 24.

Extending from the forward portion of the plate 4 are the crossed rods 26 and 27 respectively, the inner ends of which carry the supporting elements 28. As each of the securing means associated with the lower ends of the crossed rods are substantially of the same construction, the description of one is thought to suffice for the description of both. The securing means consists of a slidable member 29 which has an elongated slot 30 formed adjacent the inner end thereof and the purpose of which is to provide a means for cooperation with the adjusting screw 31 which extends therethrough and is adapted to be carried by the supporting member 28. The outer end of each of the slidable members 28 has a shoulder 32 formed thereon and extends downwardly for the purpose of engaging the outer side face of the plow handles and cooperates with the side face of the supporting member 28 in clamping the handles of the plows therebetween.

60 An additional means for holding the slidable member 29 in adjusted position with respect to the supporting member 28 consisting in providing the inner end of the slidable member with the downturned portion 33 and adapted to extend transversely therethrough

is the set screw 34, the inner end of which will engage the inner side of the supporting member 28 whereby the slidable member 29 may be adjusted with respect to the supporting member and to further hold the 70 same in a clamped position on the plow handle.

It will thus be seen from the foregoing description, that a bracing means has been provided for use in connection with plow handles whereby the same may be detachably connected therefrom, means being associated therewith for preventing the accidental displacement of the plow handle engaging elements when the device is in use. 75 Furthermore, by constructing a bracing means of the above mentioned character, the same may be moved longitudinally along the handles of the plow until the desired width or space between the respective handles has been obtained to meet the necessary requirements and thereupon the bracing means may be adjusted in a locked position upon the handles to hold the same in its adjusted position.

80 The simplicity of my device furthermore enables the same to be easily and quickly actuated and will not in any way interfere with the controlling of the plow.

85 From the foregoing description of the construction of my improved device, it will be seen that I have provided a simple, inexpensive and efficient means for carrying out the objects of the invention, and while I have particularly described the elements best 90 adapted to perform the functions set forth, it is obvious that various changes in form, proportion, and in the minor details of construction may be resorted to, without departing from the spirit or sacrificing any of 95 the principles of the invention.

Having thus described my invention, what I claim is:

1. In combination with a pair of plow handles; of bracing means therefor detachably supported therebetween comprising a plate, handle engaging members slidably supported thereon, and means for actuating said members.

110 2. In combination with a pair of plow handles; of bracing means therefor detachably supported therebetween comprising a plate, handle engaging members slidably supported thereon, means for actuating said members, and means for holding the aforementioned handle engaging members in locked engagement with said handles.

115 3. In combination with a pair of plow handles; of bracing means therefor detachably supported therebetween comprising a plate, handle engaging members slidably supported thereon, means for actuating said members, supporting rods extending forwardly from said plate, and additional handle engaging members carried by said rods.

4. In combination with a pair of plow handles; of bracing means therefor detachably supported therebetween comprising a plate having longitudinally extending guide means formed therein, elongated arms slidably supported in said guide means and extending beyond the ends of said plate, handle engaging members carried by said extensions and cooperating with the outer ends of said plate for engagement with said handles, means for interconnecting said arms, and actuating the same, and means carried by said last mentioned means and cooperating with said plate for holding the handle engaging members in locked engagement with 15 said handles.

In testimony whereof I affix my signature.
OLGA B. RILEY.
